UNITED STATES PATENT OFFICE.

SEWELL M. CORBETT, OF HONOLULU, TERRITORY OF HAWAII.

FASTENER.

1,424,803.

Specification of Letters Patent. Patented Aug. 8, 1922.

Application filed September 18, 1920. Serial No. 411,304.

To all whom it may concern:

Be it known that I, SEWELL M. CORBETT, citizen of the United States, residing at Honolulu, in the county of Honolulu and Territory of Hawaii, have invented certain new and useful Improvements in Fasteners, of which the following is a specification.

This invention relates to an improved fastener and has as one of its principal objects to provide a device of this character adapted 10 for general use in securing tying strings, lacings, cords, ropes, or other flexible elements.

The invention has as a further object to 15 provide a fastener of such construction that a string may be readily engaged therewith or disengaged from the fastener while, at the same time, the fastener will operate to securely grip the string.

Another important object of the invention 20 is to provide a fastener which will hold a string without injury thereto.

And the invention has as a still further object to provide a device which will be 25 characterized by structural simplicity and, in practical use, will not be liable to break or lose its efficiency.

Other and incidental objects will appear hereinafter.

In the drawings:

Figure 1 is a perspective view showing my improved fastener in conjunction with an envelope,

Figure 2 is a perspective view showing the manner in which the blank of the fastener is bent to provide the finished device,

Figure 3 is a longitudinal sectional view taken through the fastener,

Figure 4 is a section at substantially right angles to Figure 3, and

Figure 5 is a detail plan view showing the blank from which the device is constructed.

In carrying the invention into effect, my improved device is preferably formed from a single strip of suitable resilient sheet metal and includes a base 10 widened toward its outer end and provided with spaced notches defining substantially V-shaped prongs 11 at the side edges of the base. Between these prongs projects a tail lug 12. Formed in the base medially thereof are spaced longitudinal female ribs 13 and lying between each of these ribs and the adjacent side edge of the base is an upstanding knob 14. At the inner end of the base, the strip of sheet metal is bent forwardly to provide a longi-

tudinally inclined back spring 15 diverging toward its free end away from the base and, at the forward end of said spring, the sheet metal strip is again bent rearwardly to provide a longitudinally inclined clamping tongue 16 converging inwardly toward the base. Formed from the tongue are spaced longitudinal male ribs 17 mating with the ribs 12 of the base and, as will be noted, the 60 ribs 17 extend gradually into the ribs 12 toward the inner end of said tongue. Consequently, a cord may be readily engaged beneath the tongue at its outer end and pulled forwardly between the tongue and the base 65 when the tongue will act to resiliently grip the cord between the male and female ribs of the tongue and base. A secure hold upon the cord will thus be had.

Attention is now directed to the fact that, 75 as particularly shown in Figure 3 of the drawings, the bight or bend between the base and back spring is shaped to provide a channel shaped keeper 18 having substantially parallel flat sides while the tongue 16 is 80 formed at its free end with a flat tip 19 engaging within the keeper. The tension of the back spring upon the tongue as well as the tension of the tongue itself will normally hold the tip thereof bearing against the 85 lower side wall of the keeper so that both tongue and back spring will individually operate to bear against a cord introduced between the tongue and the base. However, the presence of the cord between the tongue 90 and base will, of course, tend to flex the tongue upwardly, so that, as will be seen, the tip 19 will coact with the upper side wall of the keeper 18 for limiting the free end portion of the tongue against upward flexing. 95 The wedging action of the cord between the tongue and base will thus be communicated through the tongue to the back spring 15. The back spring will accordingly be caused to flex in conjunction with the 100 local flexing of the tongue for accommodating the cord and, as the cord is advanced toward the inner end of the base and the flexing of the tongue and back spring is increased, the grip upon the cord by the tongue 105 will be increased proportionately. This grip will be further enhanced, incident to the forward movement of the cord between the tongue and base, due to the fact that the male ribs 17 gradually extend into the female 110 ribs toward the inner end of the tongue. A cord may, of course, be engaged beneath the

tongue from either one side or the other thereof and, as will be seen, the knobs 14 will tend to prevent accidental displacement of the free end portion of the cord. In Figure 1, I have shown my improved fastener in position upon a string envelope 20 of conventional design. As will be observed, the base 10 of the fastener is seated flat against the envelope and the prongs 11 engaged therethrough and bent forwardly for securing the fastener in place. Preferably, the prongs are bent up at their free ends to provide spurs engaging through the envelope from the lower side thereof so as to prevent backward displacement of the prongs and, as will be seen, the base will prevent the fastener from rocking forwardly upon the prongs while the tail lug 12 will overcome any tendency of the fastener to rock backwardly. The string of the envelope is indicated at 21 and, as will be seen, the flap of the envelope may be easily and quickly secured in closed position by simply riding the string beneath the clamping tongue 16 of the fastener.

In practice, the fastener is preferably formed from a blank of resilient sheet metal and in Figure 5 of the drawing, I have shown the blank in detail. As will be observed, the blank is oblong in general configuration, being widened at one end portion thereof to define a base portion A. This base portion is formed at its free end with substantially V-shaped notches lying near the side edges of the blank so that said notches define the spurs 11 as well as the intermediate tail lug 12 of the fastener. Pressed downwardly from the base portion A are the female ribs 13 of the base of the fastener while from said base portion are punched up the knobs 14. Extending from the base portion A at its smaller end is the back spring portion B of the blank and extending from said back spring portion is, in turn, the clamping tongue portion C of the blank. Pressed downwardly from the clamping tongue portion C are the spaced male ribs 17 of the fastener. The blank thus formed is first bent along a transverse fold line as indicated at D for disposing the portion C beneath the portion B when the blank is again bent along another transverse fold

line as indicated at E to dispose the portion C in coacting relation to the portion A. The prongs 11 may, if desired, be bent down at 55 the time the fastener is applied. It will accordingly be seen that the fastener may be readily produced while, at the same time, the device will prove particularly effective in practical use.

Having thus described the invention, what is claimed as new is:

1. A device of the character described including a base having an overhanging forwardly bent back spring provided with a 65 clamping tongue confronting the base in coacting relation, the bend between the base and back spring being formed to provide a substantially channel shaped keeper receiving the free end portion of the tongue. 70

2. A fastener of the character described formed from a sheet metal blank bent to define a base having a back spring extending thereover and again bent to provide a clamping tongue extending from the back spring 75 in coacting relation to the base and having its free end held in the bend between the base and back spring.

3. In a fastener, the combination of a base having an overhanging back portion provided with a clamping tongue extending in spaced relation to the back portion to confront the base in coacting relation and confined at its free end by the back portion whereby the tongue and back portion will 85 flex substantially in unison while the intermediate portion of the tongue will have limited individual movement with respect to the back portion.

4. In a fastener, the combination of a base 90 having an overhanging back portion provided with a clamping tongue extending in spaced relation to the back portion to confront the base in coacting relation, there being means lying close to the free end of the tongue for supporting said end of the tongue whereby the tongue and back portion will flex substantially in unison while the intermediate portion of the tongue will have limited individual movement with respect to the 100 back portion.

In testimony whereof I affix my signature

SEWELL M. CORBETT. [L. S.]
